ELEVATED WALKING MEANS
 Dick Jones, Box 779A, Rte. 3, Chino, Calif.
 Filed May 10, 1963, Ser. No. 279,485
 1 Claim. (Cl. 3—4)

This invention relates to walking means and more particularly to an elevated walking means such as stilts, wherein a user is elevated from the ground and yet is able to walk forwardly or rearwardly in substantially a normal manner.

Prior stilts and walking means have failed to provide a user with adequate stability, nor have they provided a simple means for compactly folding and collapsing the walking means when same is being shipped or stored.

Accordingly, it is an object of the invention to provide a novel walking means which is so constructed that the user thereof can be elevated from the ground and walk therewith in substantially a normal manner and yet be provided with maximum stability. More particularly, it is an object to provide a walking means whereby the user thereof can walk by actuating his feet in a normal heel and toe inclination.

Another object of this invention is to provide an elevated walking means including a pair of stilts which are capable of being folded into a compact and efficient configuration for storage or sale purposes, which configuration results in a width and thickness substantially equal to that of a single stilt when folded.

A further object of this invention is to provide an elevated walking means having an upper shoe supporting means pivotally connected to a post and a lower supporting means in spaced, substantially parallelogram relation with the upper shoe means and similarly pivotally connected to the post.

A still further object of this invention is to provide an elevated walking means having a hand holding means at the upper end of a post, an upper shoe supporting means pivotally connected thereto and spaced inwardly from the vertical axis thereof, and a lower supporting means pivotally connected to the post at a point below the upper shoe means, in parallelogram relation with the upper shoe means, and in a line with the vertical axis of the post.

Another object of this invention is to provide an elevated walking means which laterally spreads the ground engaging members thereof so as to prevent their interlocking while walking.

It is another object of this invention to provide an elevated walking means which, while laterally spreading the ground engaging members, maintains the shoe supporting members in normal lateral position so as to comfortably accommodate the feet of a user.

A further object of this invention is to provide an elevated walking means which has an inwardly directed moment of force, thus urging the upper hand holding means inwardly against the sides of a user.

Still another object of this invention is to provide an elevated walking means including a longitudinal support post, an upper shoe supporting means pivotally connected to said support post and extending substantially transverse thereto, a lower support means pivotally connected to the support post at one end thereof, spaced downwardly from the upper shoe supporting means and positioned substantially parallel to the upper shoe supporting means, and a longitudinal connecting means pivotally connected at each end thereof to the upper and lower support means.

The invention also comprises novel details of construction and novel combinations and arrangements of parts, which will more fully appear in the course of the following description. The drawing and the description dis-

2

close a preferred embodiment of the present invention, which is given by way of illustration or example.

In the drawing:

FIG. 1 is a front elevational view of a preferred embodiment of the invention;

FIG. 2 is a side elevational view taken along line 2—2 of FIG. 1;

FIG. 3 is a top cross-sectional view taken along line 3—3 of FIG. 1; and

FIG. 4 is a fractional side elevational view taken along line 4—4 of FIG. 1.

Referring to the drawing, FIG. 1 exhibits an elevated walking means or stilts 10 preferably made of wood or the like. In normal use the instant device would comprise a pair of stilts 12, one for each leg of the user. Each one of the pair includes a main vertical post 14, having a hand holding means 16 at the upper end thereof, and an upper shoe means or shoe support 18 pivotally mounted on the inner side of the post 14 by a bolt 20, extending substantially transverse to such post, and positioned intermediate the upper and lower ends of the vertical post 14. The horizontal upper shoe support 18 is thus spaced laterally inwardly of the vertical axis of the post 14. The bolt 20 passes through the vertical midpoint of the shoe support 18 and through the vertical post 14. Washers 21 are positioned on the bolt 20 on each side of the post 14. Further, as shown in FIGS. 1 and 3 of the drawing, the upper shoe support provides a securing strap 22 to hold the foot of a user thereto. Additionally, the upper shoe support 18 conforms to the general shape of a user's shoe.

Positioned at the lower end of the vertical post 14 opposite the hand holding means 16 and below the upper shoe support 18 is a lower shoe means 24. This is the ground engaging member. The lower shoe means 24 is a member pivotally connected to the post 14 by a bolt 26, the pivot point being spaced upwardly from the horizontal surface of the lower shoe means 24 and upwardly from the lower terminus of the post 14. The lower shoe means 24 is pivotally secured to the pivot bolt 26 by a U-shaped linkage member or bracket 28. The open portion of the U-shaped member 28 is adapted to fit over the lower end of the post 14 and the bottom 29 of the member 28 is rigidly secured to the top surface of the lower shoe means 24 by any suitable screw means or bolt means. The U-shaped member 28 is sufficiently deep so as to permit such member to rotate through at least an angle of 180° in the fore-and-aft direction of the vertical post. In this connection, the lower end or terminus of the post 14 is curved as shown in FIG. 2 of the drawing so as to facilitate rotation of the linkage member 28.

The lower shoe means 24 is positioned below the lower end of the post 14 with the vertical axis of the post 14 intersecting the lower shoe means 24 near the fore-and-aft axis of the latter. Thus, the upper shoe support 18, being mounted at a position to one side of the post 14, is offset laterally inwardly from the vertical axis of the post 14 relative to the lower shoe means 24. In addition, the lower shoe means 24 conforms to the general shape of a user's shoe and the toe end 30 is upturned slightly to aid in normal walking. Secured to the underside of the lower shoe means 24 and conforming to the upturned toe end 30 is a frictional sole member 31.

Spaced forwardly of the main vertical support post 14 and laterally inwardly of the vertical axis thereof is a rigid connecting member 32. The connecting member 32 is substantially parallel to the post 14 and is pivotally connected at the ends thereof to the upper shoe support 18 and the lower shoe means 24. At its upper end the connecting member 32 is pivotally secured by a pin 34

traversing the legs of a downwardly extending U-shaped linkage member 36, which member is attached to the underside of the upper shoe support 18 by pins 37 near the outer edge of the upper shoe support. Similarly, the lower end of the connecting member 32 is pivotally secured by a pin 38 to the upwardly extending arms of a U-shaped linkage member 40, which member is attached to the topside of the lower shoe means 24 by screws or bolts 41 near the inner edge of the lower shoe means. In this connection, the pivot point at the pin 34 is preferably spaced downwardly from the pivot point at the bolt 20 and the pivot point at the pin 38 is similarly spaced downwardly from the pivot point at the bolt 26.

As a result of the above interconnected relationship, the upper shoe support 18, the vertical main post 14, the lower shoe means 24, and the connecting member 32 all define a flexible parallelogram configuration. Thus, as a user actuates his foot in a walking movement with his foot resting on the upper shoe support 18, the lower shoe support 24 moves commensurately therewith, which enables the user to simulate his normal walking action while being elevated from the ground.

In an at-rest position, with the lower shoe means 24 engaging the ground in a horizontal plane, the upper shoe support 18 is preferably inclined slightly upwardly from the horizontal as shown in FIG. 2 of the drawing, the toe end of the upper shoe support 18 being lifted slightly upwardly. This feature, while maintaining the substantially horizontal direction of the upper shoe support 18 and the general parallelogram arrangement of parts, prevents a user's foot from wedging forwardly under the securing strap 22 in such a tight fitting engagement that quick releasability in the event of a user's fall would be difficult.

As indicated above, in actual operation the instant device is utilized in pairs, for use as an elevated walking means. A user thereof mounts the device by grasping the main post 14 at the hand holding means 16 and placing a foot on the upper shoe support 18 and beneath the strap 22. In walking when mounted on the device, the user actuates his foot in a normal walking manner. Through the use of the flexible parallelogram system here employed, the lower pivoted shoe means 24 will conform to the same movements as the upper shoe support 18. Thus, while stabilizing oneself by grasping the hand holding means 16 of the post 14, a user can move forwardly by urging his feet in a forward direction and in the normal heel and toe inclination.

The lateral inward displacement of the upper shoe support 18 from the vertical axis of the post 14 and from the center of the lower shoe means 24 provides definite advantages to the user. When employing the stilts 12 the inwardly positioned shoe supports 18 enable the user to walk with his feet in a substantially normal laterally spaced relationship while at the same time the ground engaging lower shoe means 24 are spaced laterally outwardly therefrom and are therefore prevented from inadvertently engaging one another, which engagement would cause the user to lose his stability and fall. In addition, the inward displacement of the shoe supports 18 creates an inwardly directed moment of force about the bottom end of each post 14 tending to move the holding means 16 against the sides of the user. Thus, while it can be expected (as shown by the broken lines in FIG. 1 of the drawing) that a slight outward inclination of the posts 14 will occur during actual use, since the hips of a user are frequently wider than the user's normal lateral foot spacing, as long as such inclination is less than that required to vertically align the horizontal lateral mid-point of the upper shoe support 18 with the point of engagement between the post 14 and the lower shoe means 24, the downwardly directed weight of a user on the upper shoe support 18 will result in an inwardly directed moment of force which will urge the hand holding means 16 at the top of the posts 14 against the sides

of a user. This feature prevents the stilts 12 from spreading outwardly at the upper ends thereof and, further, prevents the user from being required to laterally spread the base of such stilts in order to gain an inwardly directed moment of force.

Further, the stilts 12 may be folded into an efficient compact package when not in actual use or during the shipment thereof. The folded compact configuration is achieved by rotating the upper shoe support 18 and the lower shoe means 24 about their respective pivot points in an upwardly direction (see the broken lines in FIG. 2 of the drawing). In this situation, the lower shoe means 24, being pivotally secured to the post 14 through the U-shaped linkage member 28, is enabled to swing forwardly of such pivot point, about the lower end of the post 14, and into a position substantially parallel to the vertical post 14. Meanwhile, the upper shoe support 18 is rotated into a steeply inclined position which defines less of an angle with respect to its normal substantially horizontal position than that achieved by the lower shoe means 24. This variance in angle of inclination occurs in spite of the flexible parallelogram configuration since the shoe means 24 swings forwardly of its upwardly spaced pivot point while the upper shoe support 18 merely rotates about its pivot point. In addition, the angle of inclination variance is also affected by the rigid connecting member 32 which interconnects the elements 18 and 24 as described and thus controls their relative motions. Thus, as shown in FIG. 2 of the drawing, when the elements 18 and 24 are rotated upwardly toward a folded position they lie at different angles of inclination. Accordingly, when each stilt 12 is folded in the manner above described, one of the pair may be inverted and situated with the upper surface of its upper shoe support 18 engaging the upper surface of the shoe support 18 of the other stilt 12. Thus a longitudinal compact package is created having a width and a thickness substantially equal to the width and thickness of a single folded stilt 12.

Although an exemplary embodiment of the invention has been disclosed herein for purposes of illustration, it will be understood that various minor changes, modifications and substitutions may be incorporated in such embodiment without departing from the spirit of the invention as defined in the claim which follows:

In an elevated walking means, the combination of:
 an integral, straight support post providing a hand holding means adjacent the upper end thereof, said post having a longitudinal axis;
 an upper shoe;
 a pin pivotally connecting said upper shoe to the inner side of said post for pivotal movement about an axis which is generally perpendicular to said longitudinal axis, said pin passing through said upper shoe at about the vertical midpoint thereof and supporting said upper shoe in cantilever fashion, said upper shoe being spaced laterally inwardly from the longitudinal axis of said post;
 a lower shoe;
 a generally U-shaped bracket pivotally secured to the lower end of said post for pivotal movement about an axis which is generally perpendicular to said longitudinal axis;
 means for securing said lower shoe to said bracket for pivotal movement therewith, said lower shoe being intersected by said longitudinal axis of said post and being offset outwardly from said upper shoe;
 a downwardly opening U-shaped linkage member rigidly secured to said upper shoe at a point spaced inwardly and forwardly of the longitudinal axis of said post;
 an upwardly opening U-shaped linkage member rigidly secured to said lower shoe at a point spaced inwardly and forwardly of the longitudinal axis of said post;
 a connecting member having upper and lower ends,

said upper end of said connecting member being pivotally connected to said downwardly opening linkage member and said lower end of said connecting member being pivotally connected to said upwardly opening linkage member, said connecting member being parallel to said post when said upper and lower shoes are horizontal, said upper and lower shoes being pivotable about said pin and with said bracket, respectively, from the horizontal to a collapsed position in which said shoes are generally vertical and said connecting member lies substantially along the forward edge of said post; and
 a strap secured to said upper shoe for releasably securing the foot of a user to said upper shoe.
